[57] CLAIM

The ornamental design for a training racket for baseball,
as shown and described.

DESCRIPTION

FIG. 1 is a front, top and side perspective view of the
training racket for baseball showing my new design;

FIG. 2 is a front elevational view thereof, the undis-

closed opposite side being identical;

FIG. 3 is a side elevational view thereof, the undis-

closed opposite side being identical;

FIG. 4 is a top plan view thereof; and,

FIG. 5 is a bottom plan view thereof.

FIG. 1.

FIG. 2.

FIG. 3.

FIG. 5.

FIG. 4.
